UNITED STATES PATENT OFFICE.

CHARLES ERNEST TICHENOR, OF BLOOMFIELD, KENTUCKY.

LETTER-CARRIER.

1,256,845.

Specification of Letters Patent. Patented Feb. 19, 1918.

Application filed November 27, 1916. Serial No. 133,744.

To all whom it may concern:

Be it known that I, CHARLES ERNEST TICHENOR, a citizen of the United States, residing at Bloomfield, in the county of Nelson and State of Kentucky, have invented 5 certain new and useful Improvements in Letter-Carriers, of which the following is a specification.

This invention relates to office furniture, 10 and more particularly, to an improved filing appliance for letters and the like.

It is the principal object of the invention, to provide a simple and compact filing device, which may be applied to the usual 15 desk, roll or flat top, with but slight alterations thereto, thus, providing a construction, whereby, various matters may be readily filed in classified order, the device aiming to eliminate the use of the usual pigeon hole 20 filing system.

More particularly, the present invention has reference to the novel construction and arrangement of the filing appliance, the same being of the endless carrier type, and comprising, 25 a plurality of vertically disposed supporting rollers, which have endless belts arranged thereabout, the said belts carrying thereon, transversely positioned, supporting bars, whereby a number of filing trays may 30 be held thereby.

Another important characteristic of the present invention, resides in the provision of a pivotally mounted locking bar, which is supported upon a division board and is intended 35 to be swung outwardly into engagement with one of the supporting bars, thus, causing one of the filing trays to be locked or maintained in fixed position, convenient to the user, whereby the desired matter may 40 be obtained or deposited.

Among the aims and objects of the present invention, may be recited, the provision of a device of the character mentioned, with a view to compactness and in which the number of parts are few, the construction simple, the cost of production small, and efficiency and operation high.

Other and further improvements and novel details in the construction and arrangement of parts will be appreciated from the description to follow, which for a clear understanding of the invention should be considered in connection with the accompanying drawings, which form a part hereof 55 and wherein the preferred embodiment of

the invention is shown for the purpose of illustration.

In the drawings:—

Figure 1 is a front elevation of a desk with my improved filing appliance arranged 60 thereupon,

Fig. 2 is a transverse section taken on the line 2—2 of Fig. 1 looking in the direction of the arrows,

Fig. 3 is a fragmental detail partly in section showing the arrangement and mounting of the endless carrying belt and the manner in which the filing trays are supported thereon,

Fig. 4 is a fragmental detail in perspective 70 of one of the filing trays,

Fig. 5, a fragmental top plan of the locking arm whereby, the desired filing tray may be held locked in fixed position,

Fig. 6 is a front elevation thereof, and 75

Fig. 7 is a fragmental detail partly in section showing the bracket connection between the filing tray supporting bars and the endless carrier belts.

With more particular reference to the 80 drawings, wherin like reference numerals refer to corresponding parts throughout the several views, it may be stated, that I have in the present embodiment, disclosed my filing appliance used in conjunction with 85 the conventional type of roll top desk, which desk, I shall indicate by the numeral 1. The rear portion of the desk 1 is provided with a partition wall 2, having an opening 3 arranged therein adjacent the top portion 90 of the desk. As will be noted, the partition wall is so arranged as to provide two separate and distinct chambers, one for containing the filing appliance construction and the second, for the sliding drawers and foot 95 space. Within the first mentioned chamber, there is arranged a plurality of supporting rollers 4 and 5, the same being mounted upon suitable bearings, which are journaled within the adjacent side walls of the desk frame, 100 as shown at 6 and 7. If so desired, these rollers may be supplied with the usual anti-frictional bearing means, whereby, the same may be freely rotated upon their respective bearings. An annular flange 8 is arranged 105 upon each of the supporting rollers 4 and 5, adjacent the outer marginal edges thereof, the purpose of which will be subsequently obvious.

Referring now to the construction of the 110

filings trays and the manner in which the same are mounted for travel, it will be noted that I arrange about the supporting rollers 4 and 5, endless belts, generally indicated by 5 the numeral 9, the said belts having their end portions connected by means of buckle 10, the throat of which may be passed to any one of the various openings indicated by the numeral 11, in order that the belts 10 may be properly adjusted. Laterally positioned cylindrical brackets 12 are secured to the outer surfaces of the endless carrier belts 9, by means of rivets 13 which are passed through flattened portions thereon 15 into engagement with said belts. Attention is directed to the fact that the cylindrical brackets 12 are affixed to the carrier belts in equally spaced apart relation and that the same are provided with, upon their cylindrical portions, internally arranged screw threads 14. Cylindrical bars 15, having the extremities thereof externally threaded, as at 16, are turned into engagement with the threaded portions 14 and provide for means 20 whereby the various filing trays, which are generally indicated by the numeral 17, may be pivotally supported thereon. Substantially V-shaped brackets 18 are affixed to the end walls of the filing trays 17, by means 25 of screws or the like, as at 19, and have formed in their upper extremity, annular openings 20. Thus, it will be appreciated, that the supporting bars 15 may be passed through the openings 20, consequently, providing for the desired pivotal supporting 30 means.

The filing trays 17, comprise rectangular receptacles, having top, bottom and rear walls, the front portion thereof being open 40 to permit the filing of various matters therein. It is to be also noted, that the bottom portion, indicated by the numeral 21, is slightly inclined, thereby providing for means which will prevent the various papers 45 filed within the trays from becoming displaced during the travel of the tray. A plurality of partitions 22 are arranged within the trays 17, thus, constituting a plurality of separate receptacles and enabling 50 the matter as deposited in the trays to be more accurately classified. It is to be appreciated, that various symbols, such as numerals or letters, may be affixed to the various compartments of the filing trays 17, 55 to facilitate the filing and selection of the desired papers.

In order to provide for means whereby a certain filing tray may be maintained in fixed position adjacent the opening 3 within 60 the partition wall 2, there is affixed to the division board 23, this board being secured to the end walls of the desk within the rear chamber by suitable fastening devices, a bracket 24, and pivotally mounted thereon, 65 an arm 25, the outer end of which is forked

as at 26. Should the user desire to lock a particular tray in fixed position, the arm 25 is swung outwardly until the forked end 26, engages with the adjacent supporting bar 15, consequently, maintaining the same 70 in substantially rigid position and permitting the user to remove or deposit the desired papers within the proper compartment of the filing tray. The division board 23 also provides for means, whereby those filing 75 trays before the opening 3 of the partition wall 2, will be prevented from swinging backwardly and causing the contents thereof to become displaced, the said division board serving as an efficient abutment therefor. 80

In reviewing the operation of the construction it will be noted that when the user desires to bring a particular filing tray before the opening 3, the trays are moved upwardly or downwardly, thus, causing the same to travel about the supporting rollers 4 and 5. Sufficient movement thereof, will bring the desired tray into exposed position before the opening 3. The arm 23 may be then swung outwardly until the forked end 90 26 is engaged with the adjacent supporting bar 15, whereupon the various trays, including the one desired by the user, will be locked in substantially rigid position. It will be also evident, that the annular flanges 95 8 as arranged upon the outer marginal edges of the rollers 4 and 5 provide for means whereby lateral displacement of the endless carrier belts 9 will be prevented.

As hereinbefore stated, it is to be understood, that this construction may be used in conjunction with any form of desk, or that the same may be applied to any article of furniture, wherein such a device is desirable. Also, that the filing trays, instead 100 of being of the construction as herein disclosed and described, may embody a shelving structure upon which the various papers to be filed, may be placed and secured thereon by means of resilient clips or the like. 105

Still further embodiments of the invention than those herein especially designed, may be resorted to as conditions or preference may dictate, as may be in keeping with the hereto appended claims. 110

I claim:—

1. A filing appliance, including, in combination with an article of furniture, having a rear chamber arranged therein, a plurality of spaced apart supporting rollers arranged in said chamber, endless belts disposed about said rollers, buckles for connecting the adjacent ends of said belts whereby the same may be adjusted about the rollers, a plurality of transverse bars 120 affixed to said endless belts, filing trays pivotally carried upon said transverse bars, a division board arranged within said chamber and disposed between said endless belts for preventing excessive backward swing- 125 130

- ing of said trays, and a pivotally mounted locking arm supported by said division board and engageable with said transverse bars whereby certain of the filing trays may 5 be held in fixed position.
2. In a filing appliance, the combination of a supporting casing, supporting rollers carried by said casing, endless belts passing about said rollers, transverse bars affixed 10 to said belts, filing trays pivotally carried by said bars, a pivotally supported locking arm carried by said casing, said locking arm having a forked end, said forked end being adapted to engage said bars, where- 15 by said filing trays may be retained in set positions.
3. In a filing appliance, the combination of a supporting casing, spaced rollers carried by said casing, belts passing about said 20 rollers, transverse bars secured to said belts, filing trays pivotally carried by said bars, a division board carried by said casing, brackets carried by said division board, a pivotal locking arm secured to said brackets, said 25 locking arm having a forked outer end, said forked end being adapted to engage one of said bars, whereby said filing trays may be held in set positions.
4. In a filing appliance, the combination 30 of a supporting casing, supporting rollers carried by said casing, endless belts passing about said rollers, transverse bars fixed to said belts, receiving means carried upon said bars, a pivotally supported locking arm carried by said casing, said locking arm having a forked end, said forked end being adapted to engage said bars, thus causing said 35 means to be retained in a set position.
5. In a filing appliance, the combination
- of a supporting casing, supporting rollers carried by said casing, endless belts passing about said rollers, transverse bars fixed to said belts, receiving means carried by said bars, a movably mounted locking arm carried by said casing, said locking arm having a forked end, said forked end being adapted to engage one of said bars, thus holding said receiving means in a set position.
6. In a filing appliance, the combination of a supporting casing, spaced rollers carried by said casing, belts passing about said rollers, transverse bars secured to said belts, receiving means carried by said bars, a division board carried by said casing, brackets carried by said division board, a pivotal locking arm secured to said brackets, said locking arm having a forked outer end, said forked end being adapted to engage one of said bars, thus holding said receiving means in a set position.
7. In a filing appliance, the combination of a supporting casing, spaced rollers carried by said casing, belts passing about said rollers, transverse bars secured to said belts, receiving means carried by said bars, a division board carried by said casing, brackets carried by said division board, a locking arm movably mounted upon said brackets, said locking arm having a forked outer end, said forked end being adapted to engage one of said bars, thus holding said receiving means in a set position.

In testimony whereof I affix my signature in presence of two witnesses.

CHARLES ERNEST TICHENOR.
